UNITED STATES PATENT OFFICE

EMIL WEINER AND HARRY KATIMS, OF NEW YORK, N. Y.

DESIGN FOR A TEXTILE FABRIC

Application filed July 19, 1929. Serial No. 32,123. Term of patent 3½ years.

To all whom it may concern:

Be it known that we, EMIL WEINER and HARRY KATIMS, both citizens of the United States, both residing at New York, both in the county of New York, and both in the State of New York, have invented a new, original, and ornamental Design for a Textile Fabric, of which the following is a specification, reference being had to the accompanying drawing, forming part thereof.

The figure is a face view of a textile fabric, showing our new design.

We claim:

The ornamental design for a textile fabric, as shown.

In testimony whereof we have affixed our signatures.

EMIL WEINER.
HARRY KATIMS.
